UNITED STATES PATENT OFFICE.

FRED M. OEDER AND JAMES E. WRIGHT, OF WEST BAY CITY, MICHIGAN.

DESIGN FOR A THINNING AND WEEDING SHOE FOR CULTIVATORS.

SPECIFICATION forming part of Design No. 31,251, dated July 18, 1899.

Application filed June 14, 1899. Serial No. 720,564. Term of patent 7 years.

To all whom it may concern:

Be it known that we, FRED M. OEDER and JAMES E. WRIGHT, citizens of the United States, residing at West Bay City, in the county of Bay and State of Michigan, have invented and produced a new and original Design for a Thinning and Weeding Shoe for Cultivators; and we do hereby declare the following to be a full, clear, and exact description of the same, reference being had to the accompanying drawings, forming a part thereof.

The drawings show a cultivator-shoe for use in thinning and weeding sugar-beets, chicory, and vegetables.

Figure 1 is a side view of the improved thinning-shoe. Fig. 2 is a front view. Fig. 3 is a view of the shoe as it would appear when seen from below. Fig. 4 is a perspective view.

Our design relates to the configuration of a thinning-shoe and is characterized by the contour, shape, and relative arrangement of the side and wing portions comprising the body of the shoe.

The present design is produced by flanging or bending the bottom edge 1^b of the inclined side plane 1 into a vertical position, the ver-

tical flange extending from the wing-plane 3 to the forward end of the shoe and then shearing away the forward lower edge of the vertical flange, so as to form an upwardly and forwardly extending cutting edge 1^c, that will sever the crust of the soil with a shearing motion when the shoe is pushed forward.

The second feature of our design is produced by cutting away the rear upper corner 35 of the side 1, thus forming a rearwardly and downwardly projecting back edge 1^a, extending from the top of the side 1 to the downwardly-extending wing 3.

By the design above described we produce 40 a cultivator-shoe that is light, strong, and of neat and pleasing appearance.

We claim—

The design for a thinning and weeding shoe for cultivators, as shown and described. 45

In testimony whereof we affix our signatures in presence of two witnesses.

FRED M. OEDER.
JAMES E. WRIGHT.
